[57] CLAIM

The ornamental design for a golf cart, as shown and described.

DESCRIPTION

FIG. 1 is a left side elevational view of a golf cart showing our new design, the right side elevational view being a mirror image of that shown;

FIG. 2 is a front elevational view thereof;

FIG. 3 is a top plan view thereof;

FIG. 4 is a side elevational view thereof in its folded condition;

FIG. 5 is a front perspective view thereof; and

FIG. 6 is a rear view thereof.

Fig.1.

*Fig. 2.**Fig. 3.**Fig. 4.*Fig. 6.
